UNITED STATES PATENT OFFICE.

JOHN HAMSON VENABLES AND JOSEPH HUGHES, OF TORONTO, ONTARIO,
CANADA, ASSIGNORS OF ONE-THIRD TO SAMUEL COXON, OF SAME
PLACE.

ROTARY ENGINE.

SPECIFICATION forming part of Letters Patent No. 400,021, dated March 19, 1889.

Application filed May 3, 1888. Serial No. 272,669. (No model.)

To all whom it may concern:

Be it known that we, JOHN HAMSON VENABLES and JOSEPH HUGHES, both engineers, and both of the city of Toronto, in the county of York, in the Province of Ontario, Canada, have jointly invented a certain new and useful Improvement in Rotary Engines, of which the following is a specification.

The object of the invention is to design a reversible rotary engine in which the steam may be cut off at any desired point of the revolution and the expansive power of the steam utilized; and it consists in the peculiar combinations and the construction, arrangement, and adaptation of parts, all as more fully hereinafter described and claimed.

Figure 1 is a perspective outside view of our improved rotary engine. Fig. 2 is a sectional side view showing the interior construction of the rotary-engine cylinder.

For the purpose of illustrating our invention we have chosen an ordinary link-motion valve-gear; but it will of course be understood that any class of valve or valves may be applied.

In the drawings, A represents the main steam-pipe leading from the boiler and connecting with the valve-chest B. C is a steam-port leading from the valve-chest B to one side of the cylinder D, and E is a similar steam-port leading from the valve-chest B and entering the other side of the cylinder D immediately opposite to the point where the port C enters.

F is a link supported on the spindle of the valve and connected to the driving-shaft G by the rods H and eccentrics I, as shown. We show two eccentrics and two rods, although our engine will operate with one eccentric and one rod, for the reason we will explain further on.

Each of the steam-ports C and E is provided with a cut-off valve operated by the levers J, which levers are connected to the link F, as indicated in Fig. 1.

It is of course not necessary to connect the levers which operate the cut-off valves with the link, as the link and the valves may each be operated by an independent lever.

K is a cylinder connected to and forming part of the cylinder D, so that the circle of the inner circumference of one cylinder intersects and extends into the circle of the inner circumference of the other cylinder. Consequently the piston which follows the inner circumference of one cylinder will extend into the other cylinder when passing the space connecting the two cylinders.

L is a piston, substantially egg-shaped and fixed to the driving-shaft G, and formed so that its greatest diameter extends to and is fitted against the inner circumference of the cylinder D.

M is a two-winged cam fixed to a spindle, N, suitably journaled in the cylinder K, and having fixed to its outer end a handle, O. The outer circumference of this two-winged cam M fits the inner circumference of the cylinder K, and the two wings are connected together by a curved bridge, P, which fits against the block Q, extending into and forming part of the cylinder K.

Adjustable plates operated by springs or steam may be placed at the points of contact between the piston L and the cylinder D and the two-winged cam M and its cylinder K, and between the bridge P and its block Q; but as there is no appreciable friction at these points the wear will be very slight. Each end of the cylinders D and K is closed by a cover, R, securely bolted to flanges formed on the said cylinders. Adjustable plates operated by springs or steam are placed on the inner surface of each cover R to press against and form steam-tight joints with the piston L, cam M, and curved bridge P.

As adjustable packing of the description we use is employed in other rotary engines, it is not necessary for us to illustrate its construction in this specification. There are two exhaust-ports, S, extending from the cylinder K, opposite to each other, as shown, and each exhaust-port S is provided with a cut-off valve operated by a handle, T. Two steam-pipes, U, extend into the cylinder K on either side of the block Q. These steam-pipes U are either provided with cut-off valves or are so connected to the steam-ports C and E that

steam will be only admitted through one of them at a time.

Having described the general construction of our improved rotary engine, we shall now 5 explain briefly its operation.

It will be noticed on reference to Fig. 2 that the portion of the piston L which fits against the circumference of the cylinder K has just passed the steam-port C. The valve in this 10 steam-port is assumed to be open and the exhaust-port on the same side is closed, while the steam-port E is closed and the exhaust-port on the same side open. The steam-pipe U on the right-hand side of Fig. 2 is open, 15 and the steam-pipe U on the opposite side of the block Q is closed. The pressure of the steam admitted through the open steam-pipe U, acting against the back of the wing of the cam M, which presses against the 20 cam-shaped piston L, holds the said wing against the said piston with sufficient force to form a steam-tight joint between the two, and the steam admitted through the open steam-port E forces the piston L to travel 25 in the direction indicated by the arrow until it passes the point where the circles of the cylinders D and K intersect each other, when the steam will escape through the open exhaust-port S, and the piston L must then continue 30 to travel by the force of its own momentum until it once more reaches the open steam-port. By adopting a cut-off valve operated by eccentrics, as described, the steam may be cut off from the open steam-port at any de- 35 sired point, when, of course, the expansive force of the steam will be utilized for propelling the revolving piston L. In order to reverse the engine, it is merely necessary to shift the link F, turn the two-winged cam M so as to 40 bring the opposite cam into contact with the piston L, close the ports which were previously open, and open those which were previously closed, when the piston L will be caused to

immediately revolve in the opposite direction. As the steam-ports C and E enter the cylinder K exactly opposite to each other, the relative position of the piston L to each steam-port will be the same. Consequently a single eccentric will be sufficient to operate the valve to propel the piston in either direction. 45

It will be understood that two cylinders may be coupled together and arranged so that the piston of one will be taking steam during the period that the piston of the other cylinder is passing over the dead-center. 50

What we claim as our invention is—

1. The cylinder D, provided with steam-ports, and the cylinder K, connected to and forming part of said cylinder D, substantially as described, and provided with exhaust-ports, 60 and the block Q, combined with the piston L, the two-winged cam fitting the cylinder K, and having a curved connection between the wings fitting under the block Q, and a handle to said cam connected with the valves to 65 said exhaust-ports, substantially as described.

2. A piston, L, carried on the shaft G, within the cylinder D, against the inner surface of which it fits, the steam-ports E, entering the cylinder D immediately opposite to each other, 70 as shown, in combination with the two-winged cam M, fitting the cylinder K and carried on the spindle N, the exhaust-ports S, entering the cylinder K immediately opposite to each other, the curved bridge P, connecting together 75 the two wings of the cam M and fitting against the block Q, and the steam-pipes U, arranged substantially as and for the purpose specified.

Toronto, April 26, 1888.

JOHN HAMSON VENABLES.
JOSEPH HUGHES.

In presence of—

CHARLES C. BALDWIN,
F. B. FETHERSTONHAUGH.
